(57) **CLAIM**

The ornamental design for a metal detector for locating metal objects in tires and the like, as shown and described.

DESCRIPTION

FIG. 1 is a front elevational view of a metal detector for locating metal objects in tires and the like showing my new design;

FIG. 2 is a side view, taken from the left side of FIG. 1, the right side view being a mirror image thereof;

FIG. 3 is a top plan view thereof;

FIG. 4 is a bottom plan view thereof; and,

FIG. 5 is a perspective view thereof.

The dotted line showing of a wheel and tire in FIG. 5 is for illustrative purposes only and forms no part of my design.
